UNITED STATES PATENT OFFICE.

CHARLES TATHAM, OF NEW YORK, N. Y.

APPARATUS FOR THE MANUFACTURE OF LEAD-INCASED WIRE OR CABLES FOR ELECTRIC AND OTHER PURPOSES.

No. 911,459.

Specification of Letters Patent.

Patented Feb. 2, 1909.

Application filed October 2, 1908. Serial No. 455,908.

To all whom it may concern:

Be it known that I, CHARLES TATHAM, a citizen of the United States, residing at New York, in the county of New York and State 5 of New York, have invented new and useful Improvements in Apparatus for the Manufacture of Lead-Incased Wire or Cables for Electric and other Purposes, of which the following is a specification.

10 Such articles for example as electric wires or cables have at times to be protected by a suitable covering or casing surrounding the same. Lead has been found to be a satisfactory covering but such lead must not be 15 so hot when applied as to injure or destroy the cable or wire for the intended use.

This invention has for its object to avoid such injury while allowing the cable or the like to be effectively or hermetically incased 20 or protected.

In carrying out this invention care must be taken to avoid any leaks or water becoming mingled with the lead as this would impair the efficiency of the cable.

25 This invention is set forth in the following specification and claims and illustrated in the annexed drawing in which is shown an apparatus for incasing cables or the like, the cooling means passing through the ram 30 and into the cylinder of a hydraulic press or ram, the cooling means in the cylinder being independent of and separate from the core for guiding the cable which is located at a distance from the cooling medium or the 35 channel conducting the same. In this drawing is shown a cylinder or reservoir *a* adapted to contain lead. A bottom piece *b* has a core *c* and a die *d* arranged for a wire or cable to pass therethrough. This passage

40 *d c* is so bored or arranged that as the cable travels therethrough lead from the reservoir can be pressed about and made to incase the cable, and also be preliminarily cooled to such an extent that such lead while tightly 45 inclosing the cable will not burn or injure the same.

A ram *e* will force the lead or material about the cable passing through the passage *d c*. As the cable enters the die *d* and passes

on and out of the apparatus the surrounding 50 lead will form a hard or durable and flexible protection. Preliminary cooling of the lead before it clasps or contacts with the cable is effected by a suitable medium such as water suitably applied. The ram *e* is carried by 55 cross head *p* fixed on standards *q* operated by base *r*. The cable enters core *c* and leaves at die *d* and the cooling is effected by tube *f* passing through the ram *e*. The tube has inlet *i* and outlet *k* and this tube *f* works 60 through ram *e* and is held in proper relative position in the cylinder by cross head *n* and upright supports *o* attached to the cylinder *a*.

The outer wall or shell of the water tube *f* can be made free from joints or connections 65 or all of one piece at the part which projects through the ram and into reservoir *a*. As the great pressure of ram *e* entering reservoir *a* is apt to cause any joint to loosen and as the consequent leak would injuriously effect 70 the process such leak is to be avoided.

As seen the conduit extends axially through the ram *e* and the ram can reciprocate while the conduit remains stationary.

What I claim is:—

75 1. An apparatus for incasing cables or the like comprising a reservoir for containing lead, a ram to force lead from the reservoir, a bottom piece made to communicate with the reservoir and having a core and die for 80 the passage of a cable, and a conduit for cooling medium to temper the degree of the lead as it is forced about the cable by the ram, said conduit being made to project through the ram into the reservoir and the 85 conduit in the reservoir having its outer wall closed and being separate from and independent of the core guiding the cable.

2. An apparatus for incasing cables or the like comprising a reservoir for containing 90 lead, a ram to force lead from the reservoir, a bottom piece made to communicate with the reservoir and having a core and die for the passage of a cable, and a conduit for cooling medium to temper the degree of the lead as it is forced about the cable by the ram, said conduit being made to project 95 axially through the ram into the reservoir,

a crosshead with movable base for carrying the ram and a crosshead supported on the reservoir and made to support the conduit said conduit in the reservoir having its outer 5 wall closed and being separate from and independent of the core guiding the cable.

In testimony whereof I have hereunto set

my hand in the presence of two subscribing witnesses.

CHARLES TATHAM.
